CAPPING TOOL FOR PLASTIC BARRELS CONTAINING PREGNANT MARE URINE

Russell D. Lawrence and Henry Heuchert,
Brandon, Manitoba, Canada

Filed Mar. 18, 1974, Ser. No. 452,024

Term of patent 14 years

Int. Cl. D8—05

U.S. Cl. D8—27

FIG. 1

FIG. 2

FIG. 3

FIG. 1 is a front, top perspective view of a capping tool for plastic barrels containing pregnant mare urine showing our new design;

FIG. 2 is a bottom perspective view; and

FIG. 3 is a rear top perspective view of the embodiment of FIG. 1.

We claim:

The ornamental design for a capping tool for plastic barrels containing pregnant mare urine, substantially as shown.
